FAUCET FOR USE IN WATER DISPENSERS

Carl E. Frahm and Shirley E. Frahm, both of 1428 Oak Meadow Road, Arcadia, Calif. 91006

Filed June 25, 1975, Ser. No. 590,251

Term of patent 14 years

Int. Cl. D23—01

U.S. Cl. D23—23

FIG. 1.

FIG. 2.

FIG. 3.

FIG. 4.

FIG. 5.

FIG. 1 is a top plan view of a faucet for use in water dispensers showing our new design.

FIG. 2 is a side elevational view thereof.

FIG. 3 is a bottom plan view thereof.

FIG. 4 is a front elevational view thereof.

FIG. 5 is a rear elevational view thereof.

We claim:

The ornamental design for a faucet for use in water dispensers, as shown.
